(57) **CLAIM**

The ornamental design for a power adapter, as shown and described.

DESCRIPTION

The claimed power adapter is used to be plugged in for charging an electronic device with a wire connected therebetween.

FIG. 1 is a perspective view of a power adapter showing our new design;

FIG. 2 is a front view thereof;

FIG. 3 is a rear view thereof;

FIG. 4 is a left side view thereof, the right side view being a mirror image of the left side view;

FIG. 5 is a top view thereof; and,

FIG. 6 is a bottom view thereof.

The broken lines shown in the figures are for illustrative purposes only and do not form part of the claimed design.
